UNITED STATES PATENT OFFICE

165,956

NUT CRACKER

William Henry Ammon, Los Angeles, Calif.

Application November 3, 1951, Serial No. 17,276

Term of patent 7 years

(Cl. D44—1)

To all whom it may concern:

Be it known that I, William Henry Ammon, a citizen of the United States, and a resident of Los Angeles, California, have invented a new, original, and ornamental Design for a Nut Cracker, of which the following is a specification, having reference to the accompanying drawing, forming a part hereof, and in which Figure 1 is a side elevation of a nut cracker, showing my new design, Figure 2 is a front elevation and Figure 3 is a plan view.

I claim:

The ornamental design for a nut cracker, substantially as shown.

WILLIAM HENRY AMMON.
